CLAIM

The ornamental design for a blender base, as shown and described.

DESCRIPTION

FIG. 1 is a perspective view of a blender base, showing my new design;

FIG. 2 is a front view of the blender base shown in FIG. 1;
FIG. 3 is a rear view of the blender base shown in FIG. 1;
FIG. 4 is a side view of the blender base shown in FIG. 1;
FIG. 5 is another side view of the blender base shown in FIG. 1;

FIG. 6 is a top view of the blender base shown in FIG. 1;
and,

FIG. 7 is a bottom view of the blender base shown in FIG. 1.

The broken lines in the drawings are for illustrative purposes only and form no part of the claimed design.

1 Claim, 7 Drawing Sheets**Related U.S. Application Data**

division of application No. 29/755,781, filed on Oct. 22, 2020, now Pat. No. Des. 956,471.
